MOUNTING FOR TEXTILE SPINDLES

Howard A. Simmons, Milford, Mass., assignor of
one-half to James Read Kimball, Hopedale,
Mass.

Application October 19, 1949, Serial No. 122,280

2 Claims. (Cl. 308—169)

1

This invention relates to mountings for textile spindles, and more particularly to mountings of the type including a bolster case with a bolster removably carried therein, the bolster being arranged to receive and to support a revoluble up-right spindle.

Prior mountings of this type have for the most part employed plain or sliding bearings for the spindles. There is a great demand for higher operating speeds for spindles, but with these prior plain bearings it is not feasible to operate at higher speeds, since the oil is thrown out of the bearings, the bearings overheat, and they become badly worn after a short period of use. This permits the spindle to vibrate, and the bolster has to be replaced. While various attempts have been made to construct bolsters with bearings of the antifriction (roller or ball) type, none of the prior arrangements have been entirely successful. It has been found very difficult to supply the antifriction bearings with the proper amount of oil and at the same time prevent oil from escaping. Furthermore, prior bolsters of the antifriction type could not be used with cases intended for plain bearing bolsters.

It is accordingly one object of the invention to provide an improved spindle mounting of the anti-friction type which will permit operation of the spindle at very high speeds without appreciable wearing of the various parts or escape of the lubricating oil.

It is a further object of the invention to provide an improved antifriction spindle bolster so constructed that existing cases, originally made for plain bearing bolsters, can be readily altered to receive the antifriction bolsters.

It is a further object of the invention to provide an antifriction bolster and a case therefor, these parts being of a simple and inexpensive construction and so arranged that the bolster is firmly and accurately supported in the case and yet can easily be removed therefrom whenever desired.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is a vertical section through a spindle mounting, the section being taken on the line 1—1 of Fig. 2;

Fig. 2 is a section taken on the line 2—2 of Fig. 1;

2

Fig. 3 is a section taken on the line 3—3 of Fig. 1;

Fig. 4 is a section taken on the line 4—4 of Fig. 1; and

Fig. 5 is an elevation of a bolster, partially broken away.

The embodiment illustrated comprises a horizontal beam or so-called "rail" 10 forming a part of a textile machine and having a series of spaced holes 11 extending vertically therethrough, one hole only being shown. Within the hole 11 there is mounted a bolster case in the form of an up-right tube 12 having a central bore 14 therein, the bore being open at its upper end and closed at its lower end. The upper end of the tube 12 is enlarged to provide a horizontal flange 15 which engages the upper surface of the rail 10. From one side of the flange 15 there extends a horizontal portion 16 having an upwardly projecting boss 18 on its outer end. This boss has an upwardly open cavity 19 therein for the reception of oil, this cavity being connected to the upper portion of the bore 14 by means of a horizontal passage 20. A cover plate 22 is pivotally attached by means of an upright screw 23 to the top of the boss 18 in position normally to overlie the cavity 19. Screw threads 25 are provided on the outside of the tube 12 to receive a nut 26 which may be tightened to force a washer 27 upwardly against the lower surface of the rail 10. Thus the case 12 is securely fastened to the rail. As so far described, these various parts are old and of a well-known construction.

The bolster case 12 is arranged to receive and to support a bolster comprising a vertically elongated up-right member 29. This member includes a lower portion 30 having a substantially cylindrical outer surface of a diameter such as to fit loosely within the bore 14. This portion 30 extends somewhat above the midpoint in the length of the bolster, and above the portion 30 the member 29 is slightly enlarged in diameter and formed with external screw threads 31. The upper portion of the member 29 is in the form of an up-right cylinder 33 somewhat larger in outside diameter than the screw threads 31 and terminating at its lower edge in a downwardly facing shoulder 34 located closely above the screw threads. A bore 35 extends longitudinally through the member 29, and a cylindrical counterbore 36 is provided in the upper portion 33 of the said member. Two diametrically opposed holes 38 extend through the wall of the lower portion 30 of the member 29, somewhat above the lower end thereof, two similar diametrically opposed holes 39 are provided somewhat below the

screw threads 31, and two similar diametrically opposed holes 48 are provided in the threaded portion.

A step bearing in the form of an upright cylindrical block 42 fits loosely within the lower portion of the bore 35 and projects slightly below the lower end of the member 29. A bearing socket 43 is provided in the upper end of the block 42, and an opening 44 extends transversely through the block. A small horizontal pin 46 extends through the opening 44, the ends of this pin being supported in suitable openings 47 in the adjacent portion of the member 29. As best shown in Fig. 4, the ends of the pin 46 are headed into countersunk portions of the openings 47. The pin 46 is smaller in diameter than the opening 44 in the block 42 so that the latter is loosely held in place within the bore 35.

An antifrictional radial bearing is located within the counterbore 36 in the upper portion 33 of the bolster member 29. This bearing comprises a lower washer 49, an annular outer race 50 above the washer 49, a ring 51 above the race 50, and a relatively thin upper washer 53 above the ring 51. A plurality of circumferentially spaced vertical rollers 54 are located between the lower washer 49 and the ring 51, these rollers engaging the inner surface of the race 50. A suitable cage 55 is rotatably mounted within the ring 51 and includes fingers which extend downwardly between the rollers 54 to hold them in the proper relative positions. A cylindrical sleeve 57 is pressed tightly into the upper portion of the counterbore 36 to engage the upper washer 53 and hold the various parts of the bearing in place. An inwardly extending flange 58 is provided on the upper end of the sleeve 57, this flange defining a central circular opening 59.

In order that the bolster member 29 may be firmly attached to the bolster case 12, the latter is shaped to provide a smooth upwardly facing annular surface 61 surrounding the upper end of the bore 14, and the upper portion of this bore is provided with internal screw threads 62 to receive the threads 31 on the member 29. An annular groove 64 is provided in the threaded portion of the bore 14, in communication with the passage 20, and a vertical groove 65 extends downwardly from the said passage 20 and along the bore 14 for a short distance. To facilitate assembly, recesses 66 may be provided in the outer surface of the cylindrical portion 33 of the bolster, so that a suitable spanner wrench or the like may be employed to tighten the screw threads 31-62 and bring the shoulder 34 into firm contact with the surface 61. An annular gasket may be provided between these parts if desired, but this is believed to be unnecessary in most instances. It will be noted that when the parts are assembled, the holes 48 register with the annular groove 64, the lower end of the vertical groove 65 is somewhat below the threaded portion 31 of the bolster, and the step bearing 42 rests on the bottom of the bore 14 in the bolster case.

The invention is arranged to support an upright rotatable spindle S having a cylindrical portion 67 located within and in contact with the bearing rollers 54. Below the cylindrical portion 67 the spindle tapers downwardly, and its lower end is rotatably supported in the step bearing socket 43. Above the cylindrical portion 67 the spindle tapers upwardly, and it is adapted to receive a suitable bobbin (not shown). A downwardly flaring ring 69 is pressed tightly on the

spindle in position to lie within the sleeve 57 when the parts are assembled. This ring 69 serves as an oil slinger, and it has an outside diameter slightly less than the diameter of the hole 59 so that it will not interfere with the withdrawal and replacement of the spindle. A whirl 71 of usual and well-known construction is fitted to the spindle immediately above the cylindrical portion 33 of the bolster, the whirl including a flanged pulley 72 which surrounds the said portion 33. The cover plate 22 carries an upwardly and laterally extending arm 74 which normally overlies the pulley 72 to prevent upward withdrawal of the spindle. By swinging the plate 22 about the screw 23, the arm 74 may be withdrawn from its normal or spindle-retaining position.

The operation of the apparatus will now be apparent from the above disclosure. The cavity 19 will be kept filled with oil, and the oil is free to travel through the passage 26 into the grooves 64 and 65. Oil from the groove 65 will fill the bore 14 in the bolster case 12, and oil from the bore 14 may enter the bore 35 in the bolster 29 through the holes 33 and 30. Oil from the groove 64 may enter the bore 35 through the holes 40. Thus the step bearing 42 will be submerged in oil, and with the spindle S idle the oil level in the bore 35 will be the same as that in the cavity 19, which is slightly below the bearing washer 49. When the spindle S is in rotation, the effect of the downward taper on its lower portion, in combination with centrifugal action, will be to cause oil to be carried upwardly into contact with the bearing rollers 54. Thus the bearing will be properly lubricated. If any oil should travel upwardly along the spindle to the ring 69, it will be thrown off centrifugally by this ring. The interior of the sleeve 57 provides a considerable space for the reception of any oil which may pass upwardly beyond the bearing, and since this of course will lower the oil level or head within the cavity 19, it very definitely limits the upward movement of the oil. Accordingly there is no danger of the oil overflowing the top of the bolster. Since the step bearing 42 is slightly loose in the lower end of the bore 35, it will align itself properly with the spindle.

The screw threads 31-62 and the cooperating shoulders 34-61 provide a simple and effective means for securing the bolster to the bolster case, while preventing any leakage of oil between these parts. This construction also ensures accurate positioning of the bolster, so that all the bolsters and spindles along the rail will be supported at the same height, which is very important. The bolster can be easily removed whenever desired for inspection or replacement. Bolster cases originally made for other types of bolster can be easily re-machined to receive bolsters of the novel type disclosed herein. The apparatus is relatively simple and inexpensive to manufacture, and thoroughly dependable in service. With the mechanism disclosed, it is feasible and practical to operate spindles at unusually high speeds.

Having thus described my invention, what I claim as new and desire to secure by Letters Patent is:

1. A mounting for textile spindles comprising a vertically elongated bolster case having a bore therein which is closed at its lower end, the upper end of the bore being open and surrounded by an upwardly facing surface, internal screw threads 75 within the upper portion of the bore, a vertically

elongated bolster extending downwardly into the bore and having an enlarged upper portion providing a downwardly facing shoulder, the bolster having external screw threads thereon below the shoulder engaging the screw threads in the bore, the said surface and shoulder cooperating to limit downward movement of the bolster as it is screwed into the case and to provide an oil tight annular joint, the bolster having a bore for the reception of a spindle and a counterbore in the said enlarged upper portion, a step bearing in the lower portion of the bolster bore to support the lower end of the spindle, an antifriction radial bearing mounted in the counterbore to support the spindle intermediate its length, and means to supply oil to the interior of the bolster case and thence to the interior of the bolster, the bolster case being provided with an oil passage leading to the internally threaded upper portion of its bore and with a groove which extends downwardly from the said passage and along the bore to a point below the external screw threads on the bolster.

2. A mounting for textile spindles comprising a vertically elongated bolster case having a bore therein which is closed at its lower end, the upper end of the bore being open and surrounded by an upwardly facing surface, internal screw threads within the upper portion of the bore, a vertically elongated bolster extending downwardly into the bore and having an enlarged upper portion providing a downwardly facing shoulder, the bolster having external screw threads thereon below the shoulder engaging the screw threads in the bore, the said surface and shoulder cooperating to
